UNITED STATES PATENT OFFICE.

HARRY WALKER, OF ANAHEIM, CALIFORNIA.

SEMAPHORE.

1,194,448.

Specification of Letters Patent. Patented Aug. 15, 1916.

Application filed October 23, 1915. Serial No. 57,563.

To all whom it may concern:

Be it known that I, HARRY WALKER, a citizen of the United States of America, residing at Anaheim, in the county of Orange and State of California, have invented certain new and useful Improvements in Semaphores, of which the following is a specification, reference being had therein to the accompanying drawing.

This invention relates to semaphore signals used upon automobiles and the like, and has for its object the production of a simple and efficient semaphore which may be very cheaply manufactured and efficiently operated.

Another object of this invention is the production of a simple and efficient means for throwing the signal to an operative position and at the same time permitting the signal to return to its inoperative position, through the force of gravity.

With these and other objects in view, this invention consists of certain novel combinations, constructions, and arrangements of parts as will be hereinafter fully described and claimed.

In the accompanying drawings: Figure 1 is a side elevation of an automobile, showing the attachment of the semaphore signal thereto. Fig. 2 is a rear elevation of an automobile, showing the semaphore attached thereto. Fig. 3 is a central vertical section through the semaphore. Fig. 4 is an edge view of the semaphore casing. Fig. 5 is a vertical section through the semaphore arm. Fig. 6 is a section taken on line 6—6 of Fig. 5. Fig. 7 is a section taken on line 7—7 of Fig. 3, showing the bell in position. Fig. 8 is a section taken on line 8—8 of Fig. 5. Fig. 9 is a perspective view of the semaphore operating arm. Fig. 10 is a section taken on the line X—X of Fig. 3. Fig. 11 is a section taken on line Y—Y of Fig. 2.

It should be understood that the semaphore casing may be supported in any desired or convenient manner upon the automobile or vehicle such, for instance, as to the rear of the vehicle, or to the wind shield thereof, and in fact in any desired position found convenient to the operator of the machine.

Referring to the accompanying drawings by numerals, it will be seen that 1 designates the semaphore casing which is provided upon the rear face thereof with a mirror 2, to permit the occupants of the car or auto-

mobile to readily determine as to whether or not they are being followed closely by another machine or vehicle.

The casing 1 comprises a rectangular body 60 supporting a journal shaft 2, upon which journal shaft 2 is mounted a drum 3, to which drum 3 are secured the side plates 4 of the semaphore arm 5. These side plates 4 are connected together along the rear edges 65 thereof with a channel bar 6 shaped to conform to the contour of the semaphore arm and thereby efficiently reinforce the plates 4 and permit the construction of these plates and in fact the entire mechanism of very 70 light material. A bell 7 is carried by the shaft 2 and is adapted to be operated upon by means of the clapper arm 8, which arm 8 is actuated by means of the magnets 9 of the usual bell construction or operating 75 mechanism. The plates 4 are provided with enlarged circular ends 10 having apertures 11 formed therein which apertures are preferably covered with red color sheets 12 behind which sheets is mounted an electric 80 bulb 13, supported upon a metal bracket 14. One terminal of the bulb 13 is grounded upon the bracket 14 by means of a wire 15 and the other terminal of the bulb 13 connects with a conducting wire 16, which conducting wire is clamped in engagement with one of the plates 4 by means of the bracket 17. This wire 16 is connected to one of the terminals 19, which terminal 19 is connected to any suitable source of electrical supply 90 which electrical supply is connected to the binding post 20. It of course should be understood that this electrical supply means is grounded upon the semaphore arm 5 in any suitable or desired manner to complete the 95 electrical circuit through the bulb 13 when a suitable circuit closer is operated for closing the electrical circuit through the wire 16. It is thought unnecessary to go into the detailed construction of the circuit closer 100 and electrical mechanism as the electrical connections of the device will be obvious.

A pair of electromagnets 21 are placed within the casing 1 and these electromagnets are electrically connected to a wire 22 as are 105 also the magnets 9, the wire 22 being connected to a binding post 23, which binding post 23 is connected to any suitable electrical supply source. The ground wire 24 is connected to a connecting bolt 25 which is 110 mounted upon the clamping bracket 26 for permitting one terminal or conductor for

- both the lighting and operating circuit. This electrical connection is obvious to anyone skilled in the art. An armature 27 is pivotally supported upon a bracket 28 and an angle flange 29 is secured to the arm 27 for constituting a means for engaging an electrical magnet 21. A hook 30 is formed upon the upper end of the arm 27 and a chain 31 is connected to the upper end of the arm 27 and is also keyed or connected to the drum 3 for permitting the swinging of the semaphore arm 5 to the position shown in dotted lines in Fig. 3 when the arm 27 is attracted by the magnets 21.
- 15 The casing 1 is provided with a nipple plate 32 in which nipple plate is threaded a pipe section 33 engaging a clamp 34. This clamp 34 comprises a pair of sections held together by means of the bolts 25 for firmly 20 causing the clamp to be down around a supporting rod 35, as illustrated in Fig. 2.
- From the foregoing description it will be seen that a very simple and efficient means has been produced for actuating the semaphore arm 5, whereby a signal will be given to a person in the rear of the automobile carrying the signal and audible alarm will

also be sounded to call the attention of the person following the car to the fact that a signal is given indicating the direction of 30 turn of the automobile or machine carrying the signal.

It should be further understood that a very simple and efficient construction has been produced comprising a minimum number of parts, wherein the parts used are formed of the lightest material possible and at the same time held in a very rigid position for efficient operation.

What I claim is:—

40 A signal of the class described comprising a casing, a semaphore arm, said semaphore arm comprising a pair of similarly constructed plates, a channel plate connecting said plates and extending along one side 45 of said arm for reinforcing said plates, a drum carried by said semaphore arm, an armature lever, means for attracting said armature lever, and flexible means connected to said drum and armature lever for swinging said semaphore arm.

50 In testimony whereof I hereunto affix my signature.

HARRY WALKER.
